UNITED STATES PATENT OFFICE.

RICHARD WILLIAM CHARLES BASSETT AND ARTHUR ERNEST JERRAM, OF LEICESTER, ENGLAND, ASSIGNEES, BY MESNE ASSIGNMENTS, TO UNITED SHOE MACHINERY CORPORATION, OF PATERSON, NEW JERSEY, A CORPORATION OF NEW JERSEY.

HEEL-PLATE-SCOURING MACHINE.

1,353,821.

Specification of Letters Patent. Patented Sept. 28, 1920.

Application filed March 21, 1916. Serial No. 85,612.

To all whom it may concern:

Be it known that we, RICHARD W. C. BASSETT and ARTHUR E. JERRAM, subjects of the King of England, residing at Leicester, Leicestershire, England, have invented certain Improvements in Heel-Plate-Scouring Machines, of which the following description, in connection with the accompanying drawings, is a specification, like reference characters on the drawings indicating like parts in the several figures.

This invention relates to machines for performing cleaning, abrading and like operations upon parts of boots and shoes.

Many classes of heavy footwear are protected against wear by the provision of metal plates attached thereto at points where the wear tends to be greatest and customarily such plates are of horse-shoe shape and are applied to the heel and extend around the outside edge of the top lift of the heel from one breast corner to the other. These heel plates are usually, as available in the trade, covered to some extent with scale and are more or less rough and pitted. Again as they are usually applied at some stage before the heel blacking or coloring operations their edges usually become wholly or partially covered with ink or stain, and even with natural uncolored heels the wetting to which the heel is exposed in the finishing operation tends to rust the plate. Again the heel-finishing wax to a certain extent coats the plate and enters the pits and hollows of the plate. It is desirable for a good finish that the edge or side surface of the heel plate shall be clean and bright in the finished boot or shoe.

One feature of the present invention comprises a rotary brush, a guard rigid with the hub of said brush and having an annular supporting side face contacting with the bristles of said brush near the extremities thereof, and a combined work support or tread rest and gage of segmental outline located close to the periphery of the brush. With this construction the rest or support insures that the operative face of the brush shall accurately engage the edge of the heel plate being operated upon, and the annular guard prevents sidewise spreading of the bristles which otherwise might

cause damage to the leather heel. Preferably also the tread rest or work support is adjustable across the face of the brush to provide for operating upon the edges of plates of different thickness.

These and other features of the invention, including certain details of construction and combinations of parts will be set forth in connection with an illustrative machine and pointed out in the appended claims.

In the accompanying drawings,—

Figure 1 shows a part sectional elevation of certain parts of the machine showing the heel of a shoe in position to have the edges of its plate scoured, and

Fig. 2 shows a partial side elevation.

The machine comprises a shaft 1 adapted to be rapidly rotated and to receive at its free end a circular brush. The brush is formed of bundles 2 of stiff wires and the operative surface of the brush is constituted by the ends of the bundles which ends are arranged to lie in a single row. The axes of the bundles of wires are inclined to the plane in which the free ends of the bundles lie and the bundles pass alternately through circular holes in one or other of two flanges projecting perpendicularly from a ring 3 disposed in the plane aforesaid. The inner ends of the bundles after they pass through the flanges are embedded in soft metal such as lead which is cast around them to fill up the hollows within the flanges on each side of the ring. The ring 3, together with the washers 4, 5 contacting with the outside faces of the flanges and covering the metal-filled hollows, is mounted upon a sleeve 6 and positioned thereon between a shoulder 7 on one end of the sleeve and a clamping nut 8 threaded upon the other end of the sleeve.

The sleeve is bored to fit the shaft above referred to and is held thereon, with the shoulder on the sleeve toward the free end of the shaft, by a set screw 9 which is threaded through the shoulder and engages a recess in the shaft. Mounted upon and pinned to the shaft on the side of the brush remote from the free end of the shaft is a conical metal guard 10 the purpose of which is to sustain the wires 2 against lateral spreading during use of the brush

without affecting the resiliency of the elements of the brush in the plane of rotation of the brush. The conical guard is brought to a sharp edge which bears upon 5 the sides of the bundles at a relatively short distance from their ends. The guard is slightly hollowed internally to provide space for the end of the brush sleeve and the clamping nut on the same.

10 Near to but somewhat to one side of the free end of the shaft is a combined tread rest or work support for positioning the work and controlling the effective width of the brush. This support includes a flat 15 plate 11 which has a curved cutaway portion at one side the radius of curvature of which is slightly greater than the radius of the brush (see Fig. 2). Along this cutaway side of the plate and conforming 20 thereto is fixed a thick but relatively narrow curved strip 12 having a flat surface which as hereinafter described and shown in Fig. 1 forms the actual work-supporting surface. The plate is carried on a suitably 25 disposed fixed support 13 which holds it close to the brush with the work-supporting surface of the curved strip 12 in a plane at right angles to the axis of rotation of the brush. The plate 11 is mounted by a suitable 30 clamp and slot connection 14, 15 for adjustment across the operative surface of the brush to deal with heel plates of different thicknesses. The guard 10 prevents the wires from spreading and insures action 35 upon only the side surface of a heel adjacent its tread along a uniform width of said surface from one breast corner to the other. In other words, only the edge of the plate *a* will be scoured, and no damage 40 will be caused to the surfaces of the leather portions of the heel.

In operation the plate 11 is adjusted to leave exposed, to one side of the strip 12, a width of brush, measured from the guard 45 side, corresponding to the thickness of the heel plate *a* on the work. The brush is now rotated at high speed and the heel *b* of the boot or shoe is held with the tread surface of the heel plate *a* in contact with the rest 50 12. The edge surface of the heel plate *a* is brought to bear against the brush and the work gradually turned to expose the different parts of the edge surface in turn to the action of the brush.

55 In the operation as thus carried out the rest 12 positions the work so that only a

width of the brush ends corresponding to the width of the heel plate can act on the plate, the wires at and near to the outside edges of the brush on the side opposite 60 from the work-supporting strip being prevented by the conical sharp-edged guard from spreading sidewise more than a very small amount and being thus prevented from cutting or tearing the leather of the heel lift 65 adjacent to the heel plate. Nevertheless the flexibility of the brush in the plane of rotation is not interfered with. The rest 12 acts to hold the work away from the plate 11, on which it is carried, to a sufficient distance to give clearance for hob nails such as indicated at *c* or other protectors which protectors are sometimes inserted in the top lift 70 within the horse-shoe shaped heel plate and project beyond the plane of the tread surface of the heel plate.

Having thus described our invention, what we claim and desire to secure by Letters Patent of the United States is:

1. A machine for scouring the side surface of a heel adjacent to its tread along a uniform width of said surface from one breast corner to the other, said machine having in combination, a rotary brush, a rotary guard of less diameter than the brush bearing against one side of it adjacent to its periphery, a rest for the heel tread, said rest having a curved edge the radius of curvature of which is slightly greater than the radius of the brush, and means for adjusting said rest toward and from the plane of rotation of the guard to vary the width of the heel surface being scoured.

2. A machine for scouring the side surface of a heel adjacent to its tread along a uniform width of said surface from one breast corner to the other, said machine having in combination, a rotary brush, a concave guard rigid with the hub of said brush and having an annular bristle supporting face of less diameter than that of the brush contacting with the bristles of said brush near the extremities thereof, a work support having an edge of segmental outline located close to the periphery of said brush said support being adjustable to position the work and to determine the effective width of the brush.

In testimony whereof we have signed our names to this specification.

RICHARD WILLIAM CHARLES BASSETT.
ARTHUR ERNEST JERRAM.
